UNITED STATES PATENT OFFICE.

GUSTAVE GRIMSRUD, OF ANTELOPE, MONTANA.

SEAT.

1,403,024.

Specification of Letters Patent. Patented Jan. 10, 1922.

Application filed January 21, 1920. Serial No. 353,070.

To all whom it may concern:

Be it known that I, GUSTAVE GRIMSRUD, a citizen of the United States, residing at Antelope, in the County of Sheridan and 5 State of Montana, have invented certain new and useful Improvements in Seats, of which the following is a specification.

This invention relates in general to seats and has particular reference to a structure 10 which is more specifically adapted for use in conjunction with tractors and similar machines.

One object of this invention is the production of a seat wherein the back portion is 15 so connected to the bottom of the seat that it may be easily moved as occasion may require.

Another object of this invention is the production of a seat wherein the back is slidably and pivotally mounted upon the seat bottom 20 and is provided with a latching means, wherein the seat back may be held in a normal position to surround the side and rear portions of the seat bottom in the usual manner or the latch means may be released and the 25 back slid in one direction so that it may swing downwardly for a predetermined distance to allow access easily to the seat bottom or for other purposes which may be desirable.

30 One practical form of construction and assembly of the present invention will be hereinafter described and is illustrated in the drawing, in which,

Figure 1 is a side elevation of the seat, 35 with a portion of the back being shown fragmentarily.

Figure 2 is a side elevation of the seat, showing the back in a lowered condition.

Figure 3 is a top plan view of the device, 40 with a portion of the same being shown broken away.

Figure 4 is an enlarged fragmentary sectional view taken on the line 4—4 of Figure 1.

Figure 5 is an elevation of the latch 45 member of the locking means.

In the preferred embodiment of the present invention, about to be specifically described, the seat comprises a bottom 6 having a base plate 7 secured upon the under surface 50 thereof. This base plate 7 has guide ears 8 projecting beyond the marginal edge thereof at the forward portion of the seat bottom 6 as shown in Figures 1 to 3 inclusive. A supporting shelf 9 extends from the rear portion 55 of the base plate 7 and projects for a

considerable distance beyond the rear edge of the seat bottom 6, for purposes yet to appear. It should also be understood that suitable forms of cushioning means indicated in general at 10 may be carried upon the 60 upper portion of the seat bottom 6 to constitute a supporting surface upon the seat, as may be desired.

The seat may be carried upon the usual pedestal 11 having its supporting foot 12 65 secured as shown at 13 to the seat bottom 6, thus causing the seat bottom to be rigidly supported in a desired position.

The seat back 14 is substantially U-shaped, thereby forming parallel side walls 15, 70 causing the seat back to conform in contour to the shape of the marginal edge of the seat bottom 6. The side walls 15 are provided with longitudinal slots 16 adjacent their forward ends as shown in Figures 1 and 2. 75 In order to reinforce the supporting back and side walls thereof, a reinforcing strip 17 may be provided adjacent the base of the supporting back and obviously this strip will also be provided with longitudinally extending slots 16' registering with slots 16. Headed studs 18 are carried by the seat bottom 6 and extend through the slots 16 and 16' as shown in Figures 1, 2 and 4. It will therefore be apparent that the seat back may rest 85 upon the ears 8 and shelf 9 as illustrated in Figure 1 or it may be slid rearwardly by sliding along the ears 8 and shelf 9, the provision of the slots 16 and 16' permitting this movement. When the supporting back has 90 been moved far enough rearwardly, it will disengage the shelf 9 and then may swing downwardly by pivoting upon the studs 18 although this downward movement will be limited by the bearing of the side walls 95 upon the rear edge portions of the ears 8 as shown in Figure 2.

Now in order to prevent this seat back from accidentally shifting rearwardly and swinging downwardly, a latching means is 100 provided. This latching means includes a latch shown in general in Figure 5, consisting of a body 19 having an inwardly projecting extension 20 terminating in an upwardly extending lug 21. The upper end 105 of the body 19 is provided with a projection 22. This body 19 passes through a guide bracket 23 and a spring 24 is carried by this body 19 as shown in Figure 1. One end of the spring 24 bears upon the bracket 23 while 110

the opposite end of the spring bears upon the plate 25 fixed upon the body 19, whereby the resiliency of the spring will normally force the latch upwardly. Accordingly, as the 5 latch is fixed upon one of the side walls of the supporting back of the seat, the lug 21 thereof may pass into the socket 26 formed in the under surface of the seat bottom 6 and thus hold the seat back and the side walls 10 thereof from accidentally moving rearwardly.

Now in order to actuate this latch a lever 27 is provided and is pivotally supported upon a block 28 carried by one of the walls 15 15. The extension 22 of the latch passes through the forward end of the lever 27. The rear end of the lever is reduced as shown at 29 and is carried within a retaining loop 30 to hold the lever against displacement.

20 It is well known that very often the space between the drivers of a tractor engine is very restricted and the seat is generally placed within the space referred to. Accordingly, it is very often difficult to mount 25 upon the seat and furthermore after the operator has been operating the machine for a considerable time, the cramped position he is forced to assume tires him greatly. Yet with the ordinary form of seat now in use, 30 which are of the one-piece rigid construction, the operator cannot so change his position as to relax from the cramped position he has so long been assuming. Under normal conditions, the seat as hereinbefore described assumes the condition shown in 35 Figure 1. When however the operator desires to mount upon the seat he may grip the lever 27 and swing the same upwardly at its rear end, thus causing the forward end of 40 the lever to move the latch downwardly, whereby the lug 21 will disengage the socket 26 of the seat bottom 6. Now the operator may very easily pull the supporting back and the side walls thereof rearwardly, as 45 they will slide unrestricted across the upper surfaces of the ears 8 and the shelf 9. As soon as the supporting back disengages the shelf it will swing downwardly until the under edges of the side walls will engage the 50 rear edges of the ears 8 whereby downward movement of the supporting back is then limited. As above noted, the seat bottom 6 may be provided with a cushioning pad or suitable cushioning means 10 and it should 55 further be understood that the inner surfaces of the supporting back and the side walls thereof may be provided with a cushioning means 10'. Now, when the seat back has reached its lowermost position it will be 60 seen that it is substantially in alignment with the horizontal plane of the seat bottom 6. Therefore, the operator may very easily slide over the upper portions of the seat without interference from the supporting 65 back or the side walls and may thus assume

a position upon the seat. He may then lift the supporting back upwardly and then pull the same forwardly so that it will again assume its normal elevated position and the lug 21 will snap back into the socket 26, thus 70 locking the seat back in position upon the seat bottom 6. The operator will then have a reinforcement for his back as he operates the machine upon which the seat is carried. If however, after continuous operation for a 75 long period, he becomes cramped, he may then shift the lever 27 to cause the latch to disengage the seat bottom and the supporting back may be swung downwardly to the position shown in Figure 2. At such time, 80 it will be apparent considerable more space will be provided adjacent the marginal edge of the seat bottom 6 and particularly at the rear thereof, whereby the operator may shift about to change his cramped position and relieve him of fatigue, which could not be done if the back and bottom of the seat were a unitary one-piece structure incapable of changing positions relative to each other to permit the operator to have a differently arranged structure permitting of shifting or changing about thereupon as desired.

It would seem a very efficient seat has been provided, particularly adapted for tractors and like devices. The supporting back 90 and the side walls thereof may be moved to assume normal positions when desired to constitute a support for the back of the operator or may be shifted to a lowered position to permit of increased area about the 100 seat bottom to permit the operator to move about and ease himself of a cramped position when desirable. Therefore, the provision of latching means causes the supporting back to be releasably held in a fixed position, although the provision of the ears and the shelf relieves the latching means of supporting strain. When desired however, the latching means may be released and the 105 supporting back slid for the purposes hereinbefore set forth.

The foregoing drawing and description has reference to the preferred or approved form of the invention. It is to be understood however that I may make such changes 115 in construction and assembly of parts, materials, dimensions, etc., as may prove expedient and come within the scope of the appended claims.

Having thus fully described my invention what I claim as new and desire to secure by Letters Patent is:—

1. A seat comprising a bottom having a shelf portion, and a back slidably and pivotally associated with the bottom and adapted to normally engage said shelf portion for support.

2. A seat comprising a bottom, a back mounted upon said bottom and provided with side walls having slots, and means car-

ried by the bottom and engaging said slots whereby the back is slidably and pivotally connected to the bottom.

3. In a seat, the combination of a bottom 5 having a supporting plate thereon provided with oppositely extending side ears and a rearwardly projecting supporting shelf, a seat back slidably and pivotally mounted upon said bottom and normally resting upon 10 said ears and shelf to be held in an upright position, said back also being capable of being slid across said ears and shelf to disengage the shelf and swing downwardly.

4. In a seat, the combination of a bottom, 15 a back slidably and pivotally mounted upon said bottom, means extending from said bottom and engaging under said back for supporting the same, and a latch means releasably holding said back in a set position upon 20 said last mentioned means.

5. In a device of the character described, the combination of a bottom having supporting ears extending from the side portions thereof and a supporting shelf projecting from the rear portion thereof, a supporting back having side walls, said side walls having slots therein, headed studs carried by said bottom and extending through 25 said slots, whereby said seat back is slidably

and pivotally supported upon said bottom, 30 said back normally resting upon said ears and shelf, as and for the purposes set forth.

6. In a device of the character described, the combination of a seat bottom having oppositely extending ears projecting from the 35 sides thereof and a shelf extending from the rear portion thereof, a reinforcing back having side walls provided with longitudinal slots, headed studs extending through said slots and being carried by said seat bottom, 40 and latching means carried by said seat back, all for the purposes set forth.

7. In a device of the character described, the combination of a seat bottom, a seat back 45 slidably and pivotally mounted upon said bottom, means carried by said bottom and engaging said back for supporting the seat, a latching means including a spring pressed latch, a pivotal lever connected to said latch for actuating the same, said latch normally 50 engaging said seat bottom, as and for the purposes set forth.

In testimony whereof I affix my signature in presence of two witnesses.

GUSTAVE GRIMSRUD.
